UNITED STATES PATENT OFFICE.

M. B. STAFFORD, OF NEW YORK, N. Y.

STOVE.

Specification of Letters Patent No. 31,751, dated March 19, 1861.

To all whom it may concern:

Be it known that I, M. B. STAFFORD, of No. 46 Park Place, in the city, county, and State of New York, have invented a new 5 and Improved Radiating and Air-Heating Stove; and I do hereby declare that the following is a full, clear, and exact description of the same, reference being had to the annexed drawings, making a part of this 10 specification, in which—

Figure 1, is a vertical central section of my invention, *x*, *x*, Fig. 1, indicating the plane of section. Fig. 2, a horizontal section of the same, taken in the line *y*, *y*, Fig. 1.

15 Similar letters of reference indicate corresponding parts in the two figures.

To enable those skilled in the art to fully understand and construct my invention, I will proceed to describe it.

20 A. represents a stove which may be of the ordinary cylinder or other proper form, placed on a hollow base B, containing an ash-drawer C, as usual.

D, is the draft or smoke pipe which projects from the upper part of the stove as shown in Fig. 1.

E, is a jacket which is of semi-cylindrical form fitted on the base B, and around the back part of the stove. This jacket is a section 30 of a cylinder which is larger in diameter than the stove A, and a space *a*, is consequently allowed between the jacket and the back part of the stove. The jacket E, has a top plate *b*, the inner end of which is 35 in contact with the stove A.

The space *a*, forms an air-heating chamber and it has a hot-air conducting pipe F, projecting from its upper end. The jacket E, extends upward about two thirds the 40 height of the stove, and the upper part of the stove A, is therefore exposed, the door *c*, being in the exposed part of the stove.

The jacket E, may be of cast-iron, and cast with the stove and the base B, extends 45 sufficiently far back of the body or cylinder of the stove to admit of a register or valve G, being inserted in it to regulate the ad-

mission of cold air into the lower part of the air-heating chamber *a*, the back plate of the base having holes *d*, made in it, through 50 which holes the cold air passes, as shown by the red arrows in Fig. 1.

At the front part of the stove a perforated sheet-metal case H, is placed. This case joints the jacket E, and forms with the latter a perfect cylinder around the lower part of the cylinder or body of the stove. The perforated case H, admits of heat being radiated from the stove and also admits of cold air passing into the air-heating chamber *a*. The case H, extends upward as high 60 as the jacket E.

The upper exposed part of the cylinder or body of the stove also radiates heat within the apartment in which the stove is placed. 65

The lower part of the jacket E, has an opening or space *e*, at its lower part. This opening or space may be provided with a cover or door to close it when necessary. When a hot fire is required within the stove 70 and a considerable quantity of heated air required to pass through pipe or conductor F, the space *e*, should be open, when only a moderate quantity is required the cold air is admitted through the valve or register G, 75 and in such quantities as may be required.

I do not claim broadly a stove or fire-chamber encompassed by an air-heating chamber, for such device has been used; but,

Having thus described my invention, I 80 claim and desire to secure by Letters Patent,

The construction of the jacket in two parts, one of which H is perforated so as to form a protector and radiating chamber 85 while the other part E forms a hot air chamber, when the said parts are arranged together and with the stove and air chamber, and the whole is made in the manner herein shown and described.

M. B. STAFFORD.
